UNITED STATES PATENT OFFICE.

KENNETH L. FRANCIS, OF DENVER, COLORADO, ASSIGNOR TO ALBERT SECHRIST MANUFACTURING COMPANY, OF DENVER, COLORADO, A CORPORATION OF COLORADO.

DESIGN FOR A LIGHTING FIXTURE.

Application filed May 4, 1926. Serial No. 17,553. Term of patent 7 years.

To all whom it may concern:

Be it known that I, KENNETH L. FRANCIS, a citizen of the United States, residing in the city and county of Denver, State of Colorado, have invented a new, original, and ornamental Design for a Lighting Fixture, of which the following is a specification, reference being had to the accompanying drawing, forming part hereof.

Figure I is a front elevation of the fixture. Figure II is a side elevation of the fixture. Figure III is a plan view of the fixture.

I claim:

The ornamental design for a lighting fixture substantially as shown.

KENNETH L. FRANCIS.
